(57) **CLAIM**

The ornamental design for a lo-side truck box, as shown and described.

DESCRIPTION

FIG. 1 is a lo-side truck box in a top perspective view;

FIG. 2 is a bottom perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

In the drawings, the broken lines depict unclaimed portions of the design only and form no part of the claimed design.
